R. M. SHAW.
ELECTROLYTIC CELL.
APPLICATION FILED JULY 29, 1918.

Patented July 20, 1920.

UNITED STATES PATENT OFFICE.

ROBERT M. SHAW, OF ST. LOUIS, MISSOURI.

ELECTROLYTIC CELL.

1,346,849.

Specification of Letters Patent. Patented July 20, 1920.

Application filed July 29, 1918. Serial No. 247,096.

To all whom it may concern:

Be it known that I, ROBERT M. SHAW, a citizen of the United States, residing at the city of St. Louis, in the State of Missouri, have invented certain new and useful Improvements in Electrolytic Cells, of which the following is a full, clear, and exact specification.

My invention relates to improvements in means for electrolytically separating fluids into their component gases, and the same has for its object more particularly to provide a simple, efficient and reliable electrolytic cell by means of which a fluid may be decomposed into its constituent gases, and the gases separately conducted from the cell to suitable containers.

Further, said invention has for its object to provide an electrolytic cell in which the positive electrode may be readily removed without disturbing the electrical insulation thereof, or the supporting means therefor.

Further, said invention has for its object to provide an electrolytic cell which is so constructed that the principal parts thereof may be readily removed and placed without disturbing the electrical or mechanical balance of the cell.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings, showing an illustrative embodiment of the invention,

Figure 1 is an elevational view of an electrolytic cell constructed according to and embodying my invention, parts being broken away and shown in section, and

Fig. 2 is a sectional view taken on the line 2-2 of Fig. 1.

Referring to the drawings, 10 indicates a tank or receptacle of any suitable size and shape, and made of conducting material, such as cast or sheet metal. The receptacle 10 is provided, adjacent its upper end, with a trough 11, in which are positioned a plurality of blocks 12 formed of insulating material, and provided with recesses 13, and 14 in their upper surfaces.

For purposes of illustration the invention is shown as embodied in an electrolytic cell for obtaining hydrogen and oxygen by the

electrolytic decomposition of acid or slightly alkaline water.

15 indicates a diaphragm support, preferably made of sheet metal, having inner and outer downwardly extending flanges 16 and 17, respectively. A diaphragm 18, in the form of a bag, preferably made of asbestos fabric, has its open upper end secured to the flange 16 in any suitable manner, as, for example, by a metal strap or band 19 coacting with a groove 20 formed in the outer surface of the flange 16 adjacent its lower end. The flange 17 of the diaphragm support 15 rests within the grooves 13 of the insulating blocks 12, which are positioned within the trough 11, and the parts are so proportioned and arranged that the diaphragm support 15 will be held out of contact with the receptacle 10, as clearly shown in Fig. 1. The diaphragm 18 serves to keep the liberated gases separated below the surface of the electrolyte.

The receptacle 10 is provided with a cover 21 having a downwardly extending flange 22 which rests within the grooves 14 of the insulating blocks 12, and the height of which is such that the cover 21 is maintained out of contact with the diaphragm support 15. The cover 21 is provided with an aperture, preferably at the center thereof, within which is disposed a bushing 23, formed of insulating material, through which extends a supporting rod 24 having secured to its lower end a positive electrode 25. The upper end of the rod 24 is threaded to receive nuts 26, 26, serving to support the rod 24 and the positive electrode 25 in proper position within the receptacle 10 and also serving as a clamp for one end of an electrical conductor 27, the other end of which is connected to one terminal of a voltaic cell or other suitable source of electric current, not shown. The conductor 28, leading from the other terminal of the source of electric current, is connected to a binding post 29 secured to the wall of the trough 11. The positive electrode 25 is made of cast or sheet metal, preferably corresponding in shape with the shape of the receptacle 10, and is of such a size that it will pass easily through the diaphragm support 15.

30 denotes a gas outlet, in the form of a tube of any convenient size and length, carried by and extending through the cover 21 and communicating with the space within the depending flange 16 of the diaphragm

support 15, and 31 denotes a similar outlet, carried by and extending through the wall of the receptacle 10 and communicating with the space between the receptacle 10 and the 5 diaphragm support 15.

In order effectually to prevent the liberated gases from escaping from the cell, other than through the gas outlets 30, 31, the trough 11 is filled with a suitable liquid 32, 10 such as oil.

The operation of the apparatus is as follows:

When the proper electric current is supplied to the apparatus, it will flow from the 15 source of electric current through conductor 27, to the rod 24 and positive electrode 25, through the electrolyte, to the receptacle 10, constituting the negative electrode of the cell, and back to the source of electric energy 20 through the conductor 28. The passage of the current through the electrolyte will decompose the same into its constituent gases, which will be maintained in separated relation to one another by means of the diaphragm 25 18. The gases liberated at the positive electrode 25 will pass from the cell through the tubular outlet 30, and the gases liberated at the negative electrode or receptacle 10 will pass through the tubular outlet 30 31. The outlets 30 and 31 may be connected to any suitable containers adapted to receive the liberated gases.

It will be noted that the cover 21 and diaphragm support 15 are held against movement relatively to one another and to the receptacle 10 by reason of the fact that the depending flanges 22 and 17 rest within the grooves 14 and 13, respectively, of the insulating blocks 12.

40 When it is desired to remove the positive electrode 25 it is merely necessary to lift the cover 21 from the receptacle 10, and it will be seen that the removal of the positive electrode 25 will be effected without disturbing the diaphragm support 15 or the diaphragm 45 18 carried thereby. After the positive electrode 25 has been thus removed, the diaphragm support 15 and the diaphragm 18, may be readily lifted from the receptacle 10.

50 It will thus be seen that the several parts of the cell may be readily separated from one another when it is desired to have access to the interior of the cell, or to inspect the several parts for any purpose, as for example, when it is necessary to clean or repair any of the parts.

Having thus described my said invention, what I claim and desire to secure by Letters Patent is:—

60 1. An apparatus of the character described comprising a receptacle constituting an electrode, a diaphragm-carrying member removably supported upon said receptacle, a diaphragm carried by said member, an 65 electrode removably supported upon said

receptacle independently of said member, said electrode being insulated from said receptacle and extending within said diaphragm, and means for separately conducting the gases from said receptacle, substantially as specified. 70

2. An apparatus of the character described comprising a receptacle constituting an electrode, a member removably supported upon said receptacle, a diaphragm carried by said member, a second member removably supported upon said receptacle, an electrode carried by said second member and insulated from said receptacle and extending within said diaphragm, and means for 75 80 separately conducting the gases from said receptacle, substantially as specified.

3. An apparatus of the character described comprising a receptacle constituting an electrode, a diaphragm-carrying member 85 removably supported upon said receptacle and insulated therefrom, a diaphragm carried by said member, a cover removably supported upon said receptacle and insulated therefrom, an electrode carried by said cover and extending within said diaphragm, and means for 90 95 separately conducting the gases from said receptacle, substantially as specified.

4. An apparatus of the character described comprising a receptacle constituting an electrode, a diaphragm-carrying member 95 removably supported upon said receptacle and insulated therefrom, a diaphragm carried by said member, a cover removably supported upon said receptacle and insulated therefrom, a rod supported by said cover and extending within said receptacle, an electrode carried by said rod at the lower end thereof, and means for 100 105 separately conducting the gases from said receptacle, substantially as specified.

5. An apparatus of the character described comprising a receptacle constituting an electrode, insulating means positioned 110 upon said receptacle, a diaphragm-carrying member supported upon said insulating means, a diaphragm carried by said member, a cover supported upon said insulating means, an electrode carried by said cover 115 and extending within said diaphragm, and means for separately conducting the gases from said receptacle, substantially as specified.

6. An apparatus of the character described comprising a receptacle constituting an electrode, insulating means positioned upon said receptacle, a diaphragm-carrying member supported upon said insulating means, a diaphragm carried by said member, a cover supported upon said insulating means, an electrode carried by said cover and extending within said diaphragm, said 120 125 insulating means being provided with means to hold said diaphragm-carrying member 130

and said cover against movement relatively to one another and to said receptacle, and means for separately conducting the gases from said receptacle, substantially as specified.

7. An apparatus of the character described comprising a receptacle constituting an electrode and provided with a trough adjacent its upper end, insulating means positioned within said trough, a diaphragm-carrying member supported upon said insulating means, a diaphragm carried by said member, a cover supported upon said insulating means, an electrode carried by said cover and extending within said diaphragm, and means for separately conducting the gases from said receptacle, substantially as specified.

8. An apparatus of the character described comprising a receptacle constituting an electrode and provided with a trough adjacent its upper end, a plurality of insulating blocks positioned within said trough, a diaphragm-carrying member having a flange extending within said trough and resting upon said blocks, a diaphragm carried by said member, a cover having a flange extending within said trough and resting upon said blocks, an electrode carried by said cover and extending within said dia-

phragm, and means for separately conducting the gases from said receptacle, substantially as specified.

9. An apparatus of the character described comprising a receptacle constituting an electrode and provided with a trough adjacent its upper end, a plurality of insulating blocks positioned within said trough and provided with inner and outer grooves spaced from one another, a diaphragm-carrying member having a flange extending within said trough and resting upon said blocks in engagement with the inner grooves thereof, a diaphragm carried by said member, a cover having a flange extending within said trough and resting upon said blocks in engagement with the outer grooves thereof, an electrode carried by said cover and extending within said diaphragm, and means for separately conducting the gases from said receptacle, substantially as specified.

Signed at the city of St. Louis, in the State of Missouri, this 28th day of May, one thousand nine hundred and eighteen.

ROBERT M. SHAW.
